UNITED STATES PATENT OFFICE.

LEOPOLD HAUSER, OF NEW YORK, N. Y., ASSIGNOR TO HAUSER & WEIL, OF NEW YORK, N. Y., A COPARTNERSHIP COMPOSED OF LEOPOLD HAUSER AND SIMON WEIL.

DESIGN FOR A BUCKLE.

58,480.

Specification for Design.

Patented July 26, 1921.

Application filed December 24, 1920. Serial No. 433,076. Term of patent 14 years.

To all whom it may concern:

Be it known that I, LEOPOLD HAUSER, a citizen of the United States, and a resident of the borough of Manhattan, city of New York, county and State of New York, have invented a new, original, and ornamental Design for Buckles, of which the following is a specification, reference being had to

the accompanying drawings, forming part thereof.

The figure is a view in elevation of a buckle showing my new design.

I claim:

The ornamental design for a buckle as shown.

LEOPOLD HAUSER.
